FLOODLIGHTING LUMINAIRE

Donald E. Husby, Fairview Park, and Edmund L. Izzi,
North Olmsted, Ohio, assignors to Westinghouse Electric
Corporation, a corporation of Pennsylvania

Filed Oct. 21, 1964, Ser. No. 82,268

Term of patent 14 years

(Cl. D48—20)

FIGURE 1 is a perspective view of a complete floodlighting luminaire, showing our new design;

FIG. 2 is a side elevational view of the floodlighting luminaire shown in FIG. 1;

FIG. 3 is a front elevational view of the floodlighting luminaire shown in FIG. 1, and

FIG. 4 is a top plan view of the floodlighting luminaire shown in FIG. 1.

The dominant features of our design are indicated by full lines.

We claim:

The ornamental design for a floodlighting luminaire, substantially as shown and described.
